UNITED STATES PATENT OFFICE.

SISSAK K. OUZOUN-BOGHOSSIAN, OF WASHINGTON, DISTRICT OF COLUMBIA.

DESIGN FOR A TYPEWRITER-FRAME.

55,812.

Specification for Design.

Patented July 13, 1920.

Application filed December 5, 1919. Serial No. 342,845. Term of patent 3½ years.

To all whom it may concern:

Be it known that I, SISSAK K. OUZOUN-BOGHOSSIAN, a subject of the Sultan of Turkey, having declared my intention of becoming a citizen of the United States, residing at Washington, District of Columbia, have invented a new, original, and ornamental Design for a Typewriter-Frame, of which the following is a specification, reference being had to the accompanying drawing, forming part hereof.

Similar reference characters refer to similar parts in the two figures of the drawings.

In the drawings, Figure 1 is a front view

of a standard typewriter frame to which is fitted the typebar door A of my new design as shown. Fig. 2 is a side view of the standard typewriter frame, to which is fitted front typebar door A of my new design as shown in Fig. 1.

Having thus described my invention what I desire to secure by Letters Patent of the United States and claim is:

The ornamental design for a typewriter-frame as shown.

In testimony whereof I affix my signature.

SISSAK K. OUZOUN-BOGHOSSIAN.
